UNITED STATES PATENT OFFICE.

HENRY BLUME AND GEORGE B. STREITZ, OF JORDAN, MINNESOTA.

VALVE AND CAGE PULLER.

Application filed August 31, 1925. Serial No. 53,615.

This invention relates to devices for removing the valve cages and valve springs from motors in which valves are located in the motor head. The invention also has reference to a valve removing device of a type embodying a vertical shank having a head and impact member slidably along said shank to strike the head and exert upward impulses on the shank, so as to remove the valve, valve cage and spring, when the lower end of the shank is connected operatively with these parts. Heretofore, it has been customary to provide resilient legs on the lower end of the shank, said legs being adapted to engage the usual valve spring cap at the upper end of the valve stem. Much difficulty however is encountered in engaging the legs with the cap, and when applying the tool as well as when operating it, there is danger of injuring the cap as well as the valve stem, and possibly the valve proper also. It is the intent of our invention however to provide a new and improved construction in which the legs at the lower end of the shank are of different lengths to accurately engage a convolution of the valve spring at diametrically opposite points, said legs having hooks to engage the spring. These hooks may be easily engaged with the spring by lateral shifting of the tool with respect to said spring and when each impact is imparted to the shank by the slidable impact member, such impact is cushioned as it is transferred to the valve, through the instrumentality of the spring. Thus, not only may the device be applied to the valve much more easily than similar devices heretofore in use, but as each blow of the impact member is cushioned by the valve spring, there is no danger of injuring any part of the valve assembly.

Figure 1 is a side elevation of a valve removing tool constructed in accordance with our invention.

Figure 2 is a smaller view of the tool in elevation and illustrating it operatively associated with a valve assembly, before removing the latter.

In the drawings above briefly described, the numeral 1 designates a straight shank having a knocking head 2 at its upper end and provided at its lower end with diametrically opposed, longitudinally extending

legs 3 and 4 which are adapted to straddle the upper end of a valve spring 5 and its usual cap 6. The legs 3 and 4 are of different lengths and they are provided at their extremities with inwardly projecting hooks 7 and 8 respectively, said hooks being adapted to hook under diametrically opposed portions of a convolution of the spring 5, as shown fully in Figure 2. The hooks may be readily engaged with the spring, by shifting the tool laterally with respect to said spring, and it is unnecessary to form the legs 3 and 4 from resilient material as has heretofore been done when such legs must be engaged with the valve cap.

An impact member 9 is shown slidably mounted upon the shank 1 and adapted to be forced upwardly along the same into contact with the knocking head 2. When this is done, an upward force is exerted on the shank and the legs 3 and 4, and this force is transferred by the hooks 7 and 8 to the spring 5, which in turn yieldably transfers such force to the valve cap 6. Thus, the latter pulls upwardly upon the valve stem 10, causing the valve proper 11 to thrust upwardly upon the usual cage 12. It will thus be seen that by repeatedly shifting the impact member 9 upwardly, forcible upward impulses will be imparted to the valve assembly to remove it from the cylinder head, and even though these impulses are sufficiently forcible to obtain the desired result, there is no possibility of injuring any parts of the valve assembly, as all impulses are cushioned by the upper portion of the spring 5, as they are imparted to said assembly.

Excellent results are obtainable from the details disclosed and they are therefore preferably followed. However, within the scope of the invention as claimed, slight modifications may be made.

We claim:

A removing tool for an overhead valve comprising a shank having a knocking head at its upper end and provided at its lower end with a pair of laterally spaced longitudinally extending integral legs parallel to and offset from said shank at their junction with the shank and adapted to straddle the valve stem cap and the upper portion of the valve spring, said legs being of different

lengths and having inwardly turned hooks at their extremities to engage under diametrically opposite portions of a convolution of the valve spring, and an impulse member slidably mounted on the shank for co-action with said knocking head in producing upward impulses on the tool, which

impulses are yieldably imparted to the valve assembly by the engagement of the hooks with the spring of said assembly. ¹⁰

In testimony whereof we have hereunto affixed our signatures.

HENRY BLUME.
GEORGE B. STREITZ.
